APPARATUS FOR FRACTIONATING
NATURAL GAS

John L. Hall, Charleston, W. Va., assignor of one-half to Danciger Oil and Refineries, Inc., Fort Worth, Tex., a corporation of Texas

Original application December 28, 1939, Serial No. 311,415, now Patent No. 2,295,211, dated September 8, 1942. Divided and this application June 3, 1940, Serial No. 338,601

9 Claims. (Cl. 62—122)

This invention relates to an improved apparatus for fractionating natural gas.

This application is a division of prior application Serial No. 311,415, filed December 28, 1939 now Patent No. 2,295,211, granted September 8, 1942.

In the past many methods have been proposed for effecting the separation of hydrocarbon liquids from natural and artificial hydrocarbon gas mixtures. Such a separation does not present any great difficulty at relatively low pressures, i. e. up to about to 700 to 800 lbs. However, at more elevated pressures fractionation becomes very difficult. In order to obviate the difficulties inherent in such high pressure fractionation, it has been the practice to initially reduce the pressure and then to proceed with fractionation at such reduced pressure range.

Such a method of procedure is a distinct disadvantage in many types of operation as for example, in cyclic processes in which natural or casinghead gas is withdrawn from a well for extraction of certain constituents and the residue gas is returned to the producing horizon. In the past when the operating pressure on the well was high it was felt necessary to reduce the pressure in order to secure the desired fractionation. A natural concomitant of the drop in pressure was a marked expansion of the gas thus requiring greater volumetric capacities in the treating apparatus and a larger expenditure of power in recompressing the gas for repressuring the well.

It has been discovered that eminently satisfactory fractionation of these hydrocarbon mixtures may be effected under any pressure up to several thousand pounds per square inch and without any reduction in pressure of the gas other than that which is an incident of the static resistance of the treating system.

The striking advantages of such a method of operation will at once be apparent. With such a high pressure fractionation it becomes possible, in most instances, to directly return the residue gas back to the producing horizon with but little if any compression, thus effecting large savings in power cost. Such a system operating at substantially well pressure permits the use of compact apparatus of small volumetric capacity as compared to earlier systems.

In order to enable a more ready comprehension of the principles of the invention a typical operation will be described in conjunction with the illustrative apparatus shown in the accompanying drawing. In the drawing Figure 1 is an elevation view of fractionating tower and associated units and Figure 2 is an enlarged detail of the reboiler unit of Figure 1.

Figure 3 is an enlarged detail, partly in section of the coolers and associated parts.

As shown in the drawing, the essential elements of the apparatus unit include a fractionating tower A, a reboiler unit B, connected with the base of the tower and a preheater unit C. The fractionating tower A may be of any suitable size and in the illustrative embodiment comprises a tower about 53 ft. high and about 6 in. in diameter. This tower preferably is packed with iron Raschig rings and is adapted to be maintained under pressure and, in conjunction with the preheater and reboiler, serves to fractionate the incoming gases under substantially the pressure obtaining in the well. The unit may be connected to a well through the line 1. As shown in the drawings this line enters the heat exchanger 2 and is connected at its discharge end to the gas line 3 which communicates with the tower A at a low point and below baffle 4. The gases passing through the line 4 are adapted to be preheated in the heat exchanger 2 by hot fluids circulated to and from the reboiler unit.

Positioned adjacent the base of the tower is a reboiler system including the inclined reboiler tank 5 and the upper communicating tank 6. Tank 5 preferably is of the shell and tube type and is provided internally with a bank of tubes 5' to heat the condensate passing therethrough.

A heating medium, such as steam, may be circulated through the shell by means of the connections 7 and 8. The unit 5 is connected at its lower end through the line 9 to the bottom or kettle section of the tower A and at its upper end through line 10 to the tank 6. The reboiler tank 5 is also connected to the tank 6 through the branch line 11. As will be seen, more fully hereinafter, the reboiler units, including tanks 5 and 6 with their circuit connections 10 and 11, form a closed thermal circulation circuit through which the liquid product collecting in the base of the tower is heated and circulated. This unit comprises, in a sense, a fractional distillation zone. Lighter constituents which are evolved in the circuit, notably methane and ethane, pass overhead from tank 6 through the line 12 and are introduced into the tower A at an intermediate point, preferably about 20 ft. up from the base of the tower.

The reboiler system is interconnected with the heat exchanger 2. For this purpose line 13 is connected with the upper section of line 11 at one end and to the shell of heat exchanger 2 at the other. Preferably the leveling box 14 is interposed in the circuit. Hot fluids introduced

into the heat exchanger 2 are withdrawn through the line 15 controlled by valve 15'. A portion of these fluids are passed through the line 16 and pressure control valve 17 into the upper cooling section of the tower. The remainder of the hot liquid products in the heat exchanger are passed through pump 18 and line 19 into an intermediate section of the tower A to serve as a scrubbing liquid. It is particularly to be observed that the inlet for the reflux liquid is positioned below the inlet of gas line 12.

The upper section of the tower A comprises the serially arranged coolers 20 and 21. These are preferably of the internal tube type. Connected to the cooler 20 are the inlet and outlet lines 23 and 23' respectively, through which the cooling medium, such as water, is introduced and withdrawn. Interposed between coolers 20 and 21 is an intermediate section 22. The tower sections 20, 21 and 22 are shown as being detachably secured; if desired these may be welded. In operation, gases which pass upwardly through the tubes of the condenser 20, are cooled by indirect contact with the cooling medium and the gaseous products are then discharged into the line 25. Condensate collecting in the intermediate section 22 may be fed back through line 24, controlled by valve 24' to the upper section of tower A as shown.

The gases and vapors which are preliminarily cooled in the cooler 20 pass outwardly of this cooler through line 25 and are introduced into the top of the cooler 21. In passing downwardly through the interior tubes of this cooler the gases are further cooled by indirect heat exchange with an expanded and cooled fraction from the preheater introduced through the expansion valve 17. Expansion of the liquid products passing through line 18 commensurately reduces the temperature to give a refrigeration cooling.

The condensate and vapors formed in the cooler 21 as a result of this expansion and cooling is withdrawn through line 30 controlled by valve 30' and passed through a suitable stabilizer (not shown) to recover the valuable constituents, as for example a natural gasoline fraction.

The cooled gases, consisting largely of methane and ethane, are withdrawn from the lower end of the tubes in cooler 21 and discharged from the system through line 31. Pressure may be maintained on this line by valves 31' and 34'.

In one method of operation, high pressure gases from line 31 may be discharged directly into a residue well through the line 31 and branch line 34, controlled by valve 34'. When it is desired to increase the pressure on these gases, prior to delivery to a well, line 31 may be connected to the intake side of compressor 33 by opening valve 31' and the gas at any desired higher pressure may be forced into a well through line 35. During the operation of the system, the excess of the liquid fraction accumulating in the reboiler system may intermittently or continuously be removed through line 36 controlled by valve 36' and subjected to any desired type of treatment. It may for example be passed to a stabilization unit or to a unit for the production of polymer gasoline.

It will be appreciated that the described apparatus enables the operation of a novel and highly effective process. This process may be employed for treating natural gas for the recovery of heavier valuable constituents, e. g. propane or butane and the like, and repressuring a producing horizon; similarly the system

may be employed for processing a wet gas to recover a casinghead gasoline fraction as well as other valuable heavy constituents of the raw gas and the residue reintroduced into the producing horizon. It will be understood that when the process is utilized for treating casinghead gases a separator is interposed between the well and tower to remove the heavy oil prior to fractionation of the gases.

10 The operation, in sharp contradistinction to prior methods, is carried out at well pressure (or if desired at higher than well pressure). In carrying out the process, the tower A is first charged with a mixture of butane, propane and pentane introduced through line 40. Raw gas from a primary source, such as a gas well, and, in a typical case, at a pressure of substantially 2700 lbs., and a temperature of approximately 80° F. is conveyed through line 1 and thence through the internal tubes in the heat exchanger 15. During passage through the heat exchanger the gas is preheated and is then discharged through line 3 at a temperature of substantially 140° F. into the lower portion of the tower below the baffle 4. In the tower the upwardly flowing gases are contacted with a countercurrent flow of scrubbing liquid which is continuously introduced into the tower through line 19. Due to such direct contact, the liquid refluxing medium largely condenses the heavier constituents of the gas and returns these to the base of the tower.

30 The heavier condensed hydrocarbons accumulating in the base of the tower flow by gravity into the reboiler tank 5 through line 9. In the reboiler the condensate is heated by indirect contact with the steam and the temperature of the condensate is raised to the order of 230° F. Due to the increase of temperature and 40 to the expansion of occluded gases, thermal circulation is initiated and the heated liquid flows upwardly through line 10 into the denuder tank 6 and back to the reboiler through line 11. During this cycle a predetermined portion of the 45 circulating stream is withdrawn through line 13 and passed to the preheater 2 in the manner described. The quantity which is introduced into the preheater 2 is equivalent to that withdrawn from lines 30 and 36.

50 It will be appreciated that this method of split or double fractionation is as unique as it is effective. It will be observed that the liquid products from the base of the tower pass through the restricted areas of the tubes of reboiler 5 and after receiving a considerable increment of heat 55 are passed into the relatively large area in denuder tank 6. The velocity of the stream is therefore diminished in tank 6 and the lighter constituents of the mixture, principally methane and ethane, rapidly evolve and pass upwardly through line 12 into the tower A. This reboiler unit, therefore, comprises a special type of thermal distillation unit in which condensate from the bottom of the tower is fractionally distilled under the prevailing pressure of the system to remove the lighter ends and these lighter ends are reintroduced into the tower at a point spaced from the primary fractional condensation zone. The reboiler unit also serves to add a considerable amount of heat to the condensate for the purpose of preheating the incoming raw gas.

60 In the operation thus far described, it will be seen that the lower section of the system comprises two concurrently operating fractionating

systems. In the first, in the lower part of the tower itself the raw gas enters at well pressure and at a definite preheat. This stream of raw thermally expanded gas is refluxed for a predetermined portion of its travel during which constituents heavier than ethane are largely removed by fractional condensation. Thereupon the condensate is subjected to a segregated and special fractionation, namely a high pressure fractional distillation in which the more volatile components, largely methane and ethane are removed and reintroduced into the tower above the primary or condensation zone and the condensate itself is heated for the purpose of preheating the raw gas.

In the intermediate and upper sections of the tower the gas from both fractionation zones passes upwardly and are cooled and densified by direct contact with a cooling liquid introduced into the upper end of the tower through line 24. In this intermediate section the temperature of the high pressure gases is reduced to the order of about 60° F. In further passage through the cooler 20 the temperature of the gas is again reduced with resulting knock-back of heavier entrained constituents.

In the final stage of cooling the gases passing downwardly through line 25 and the tubes in cooler 21 are subjected to refrigeration cooling. The cooled gas consisting essentially of methane is thus reduced to a temperature of approximately -5° F. and is discharged through line 31 for utilization as previously described. The condensate and vapors formed in cooler 21 as a result of the expansion and cooling of liquid from preheater 2, and at a temperature of substantially -5° F., are withdrawn through line 30 and treated as desired, for example by passage through a preheater and to a suitable stabilization unit whereby desirable products such as pentane, gasoline, propane, butane and the like are separated out.

A striking feature of the present process of fractionation at high pressures is the exceedingly large capacity of a plant of the present as compared with that of earlier methods. This great capacity is established by the unique fractionation and the improved apparatus. As explained in the present method the entire system is held at substantially well pressure. On entering, the raw gas is immediately preheated and consequently expanded and then refluxed in a primary condensation zone with a continuously circulating stream of reflux liquid from which liquid the lighter constituents, especially methane, are largely removed before recycling. In these circumstances the recirculating stream of reflux liquid not only serves as a condensing medium but also, in a sense, as a methane denuding or scavenging medium.

Another salient advantage of the present method resides in the physical character of the effluent gas. Since a high partial pressure of methane obtains in the upper portion of the tower and since the system is carried at a very elevated absolute pressure the gas discharged from the system is of high density. When this gas is fed directly to a well, or through a compressor and thence to a well, this high density greatly facilitates the gas flow down into the well.

The improved apparatus, as noted, insures the fractionation of hydrocarbon gas mixture at high pressures. While a typical operation at 2700 lbs. per sq. in. has been described, it will be un-

derstood that the process is available for employment at a wide range of pressures, i. e. from the order of 700 lbs. per sq. in. up to several thousand pounds.

5 It will be appreciated that within the broad concept of the invention many permissive variations in mechanical arrangements of the apparatus and in operative technique are possible. All such modifications which invoke the broader principles of the invention are comprehended in the appended claims.

I claim:

1. An apparatus for fractionating high pressure natural gas which comprises an elongated fractionating tower, a line leading from a gas well to the tower, a heat exchanger in said line, a line to withdraw condensate from the base of the tower, means to heat such condensate and to force the heated condensate through the heat exchanger directly to the tower to contact preheated gases passing therethrough.

15 2. An apparatus for fractionating high pressure gas which comprises a fractionating tower, means to pass a stream of gas to the tower, a preheater associated with said means to preheat the gas passing to the tower, a reboiler unit connected with the base of the tower, means separately to withdraw a condensed liquid fraction and a gas fraction from the reboiler unit, 20 means to admit the gas fraction to the tower at an intermediate section thereof and means to admit the condensate fraction to the tower at a point below the point of admission of the gas fraction.

3. An apparatus for fractionating high pressure hydrocarbon gases which comprises an elongated fractionating tower, a gas line for passing high pressure gases to the lower section of the tower, a heat exchanger interposed in the line to preheat incoming gas, a reboiler unit connected with the base of the tower and adapted to fractionate condensate fed thereto from the tower into a condensed liquid fraction and a gas fraction, means to pass the liquid fraction from the reboiler unit through the heat exchanger and thence to an intermediate section of the tower to serve as a refluxing medium and means to pass the said gas fraction back into the tower.

4. An apparatus for fractionating high pressure hydrocarbon gases which comprises an elongated fractionating tower, a gas line for passing high pressure gases to the lower section of the tower, a heat exchanger interposed in the line to preheat incoming gas, a reboiler unit connected with the base of the tower and adapted to fractionate condensate fed thereto from the tower into a condensed liquid fraction and a gas fraction, means to pass the liquid fraction from the reboiler unit through the heat exchanger and thence to an intermediate section of the tower to serve as a refluxing medium and means to pass the said gas fraction back into the tower at a point above the point of admission of the said refluxing medium.

5. In an apparatus of the type described in which high pressure hydrocarbon gases are fractionated in a fractionating tower, a reboiler unit for fractionating condensate comprising, a reboiler connected to the base of the tower, an enlarged chamber in fluid communication with the reboiler, a gas line connected at one end to the chamber and at the other end to the tower; means to pass a heating medium in indirect heat exchange relationship with the condensate in

the reboiler to effect cyclic thermal flow of condensate from the reboiler to the chamber and back to the reboiler while continuously withdrawing evolved lighter constituents of the condensate through said gas line.

6. An apparatus for fractionating high pressure hydrocarbon gases comprising a fractionating tower in which gases are maintained at substantially well pressure and are subjected to condensation, means to denude the condensate of lighter normally gaseous constituents; means to split the denuded condensate into two streams, means to feed one of said streams to a lower portion of the tower to serve as a scrubbing liquid for incoming raw gases and means including a pressure reduction valve to feed the other stream to a cooler in an upper portion of the tower for indirect heat exchange with rectified gas and means to separately withdraw from the tower the rectified gas and the said other stream.

7. An apparatus for fractionating high pressure hydrocarbon gases comprising a fractionating tower in which gases are maintained at substantially well pressure, and are subjected to condensation, means to denude the condensate of lighter normally gaseous constituents; means to split the denuded condensate into two streams, means to feed one of said streams to a lower portion of the tower to serve as a scrubbing liquid for incoming raw gases and means including a pressure reduction valve to feed the other stream to a cooler in an upper portion of the tower for indirect heat exchange with rectified gas and means to separately withdraw from the tower the rectified gas and the said other stream and to utilize said withdrawn gas for repressuring a producing horizon.

8. In an apparatus for fractionating high pressure hydrocarbon gases a fractionating tower, a gas feed line connected with a lower section of the tower, a heat exchanger in said line, a reboiler unit connected with the lower end of the tower, a gas line connected at one end to the reboiler unit and at the other end to an intermediate section of the tower, a condensate line connected at one end to the reboiler unit and at the other end to heat exchanger, a liquid line connected at one end to the heat exchanger and at the other end to an intermediate section of the tower below the said gas line and adapted to feed condensate to the tower for direct scrubbing contact with the preheated raw gas; an expansion chamber heat exchanger positioned in the upper section of the tower, a line connecting the heat exchanger with the expansion chamber and including a pressure reducing means whereby condensate from the heat exchanger is flashed in said expansion chamber exchanger to cool gases by indirect heat exchange and separate lines to withdraw cooled rectified gas and the expanded condensate respectively.
9. An apparatus for fractionating high pressure hydrocarbon gases comprising a fractionating tower, a gas inlet line connected with the lower portion of the tower, means to heat the gas in transit to the tower, means to condense constituents of the gas in the tower, means to charge a portion of the condensate as a scrubbing liquid into the lower portion of the tower and means to charge another portion of the condensate as a refrigeration cooling medium into the upper section of the tower.

JOHN L. HALL.
